UNITED STATES PATENT OFFICE.

ADAM TYSKIEWICZ, OF ROTHSCHILD, WISCONSIN.

CONCRETE MOLD.

Application filed September 29, 1923. Serial No. 665,655.

To all whom it may concern:

Be it known that I, ADAM TYSKIEWICZ, a citizen of the United States of America, residing at Rothschild, in the county of Marathon and State of Wisconsin, have invented 5 certain new and useful Improvements in Concrete Molds, of which the following is a specification.

This invention relates to certain new and 10 useful improvements in concrete molds of the type employed in the building of floors, walls or the like wherein reinforcing I-beams are embedded in the concrete with the mold formed of separable and expandable sections.

15 The primary object of the invention is to provide a concrete mold for floors, walls or the like wherein separable and expandable mold sections are constructed in a manner for rigidly supporting reinforcing I-beams in positions, either for completely embedding the I-beam in the molded concrete or embedding the I-beam with one flange face exposed.

20 A further object of the invention is to provide a concrete mold of the above type wherein the mold sections are constructed for interlocking engagement with supporting bars that hold concrete forms or arched members properly positioned during the 25 molding operation.

With the above and other objects in view as the nature of the invention is better understood, the same consists of the novel 30 form, combination and arrangement of parts hereinafter more fully described, shown in the accompanying drawing and claimed.

In the drawing, wherein like reference 35 characters designate corresponding parts throughout the several views,

Figure 1 is a fragmentary cross-sectional view of a molded floor section showing the mold clamping block engaging the reinforcing I-beam, with the I-beam completely embedded in the concrete, the arch members or mold forms supported on the clamping block and the supporting bars for the mold forms interlocked with the clamping blocks,

40 Figure 2 is a detail sectional view taken on line II—II of Fig. 1 showing the separable and expandable mold clamping blocks,

45 Figure 3 is a cross-sectional view taken on line III—III of Fig. 2,

50 Figure 4 is a fragmentary cross-sectional view, similar to Fig. 1, showing the mold clamping blocks in their reversed position

supporting and engaging an I-beam with the lower face of one base flange exposed.

Figure 5 is a fragmentary side elevational view of a modified form of molding device, 60

Figure 6 is a perspective view of one of the mold clamping sections or blocks shown in Figs. 1, 2 and 4,

Figure 7 is a perspective view of one of the detachable clamping blocks employed in 65 the mold, and

Figure 8 shows bottom plan and perspective views of the lower end of one of the supporting bars that is interlocked with the outer end of the clamping mold.

The concrete mold disclosed in this application being intended for use in connection with the formation of flattened or plain bodies or surfaces, such as walls, floors or the like and for supporting I-beams as reinforcing elements and arch supports for the concrete during the molding operation, the mold embodies similarly formed cooperating clamping mold members, each including

70 a body portion 1 cutaway at one corner edge thereof as at 2 and carrying an upwardly directed shoulder 3 at the longitudinal edge of the cutaway portion, as clearly shown in Fig. 6. The body portion 1 is formed with a transversely extending elongated slot 35

4 so that when the two mold sections or body portions thereof are assembled as illustrated in Fig. 2, the slotted openings 4 register and have a clamping bolt 5 passing therethrough for holding the mold sections in adjusted 90

positions. The body portion 1 at the end thereof opposite the slotted opening 4 carries an elongated extension 6 having spaced cutaway portions of unequal depth upon one side thereof as at 7 and 8 to form a laterally 95

extending arm 9, while the extreme outer end of the extension member 6 carries an angularly directed arm 10 projecting in a direction opposite the arm 9, this construction being clearly shown in Figs. 2 and 6. The 100

body portion 1 is provided with an upwardly directed transversely extending rib 11 while the lower face of the body portion 1 carries a clamping lug 12 having the hook portion thereof directed toward the slotted end 4 of the body portion with a threaded opening 13 extending through the body portion as 105

shown in Fig. 6.

When the clamping sections of the mold are assembled as illustrated in Figs. 1, 2 and 4, the bolt 5 secures the mold sections in adjusted positions with the shoulders 3 abut-

110

ting each other and alined with the ribs 11

The clamping sections of the mold are arranged in spaced relations and in spaced rows with a longitudinally extending board 14 supported upon the shoulders 3 and ribs 11, a clamping block 15 illustrated in detail in Fig. 7 being positioned adjacent each side edge of the board 14 and embodying a base flange 16 resting upon the board as shown in Fig. 1 with an upper clamping flange 17 engaging the adjacent edge of the base flange 18 of a reinforcing I-beam 19 that is supported on the base flanges 16 of cooperating clamping blocks providing a space between the base flange 18 of the I-beam and the upper face of the board 14.

Arch forms are associated with the mold sections and board 14, each including an upper wall 20 and depending side walls 21, the lower ends of which rest upon opposite edges of the board 14, the arch forms being further supported by an upper horizontal bar 22 engaging the lower face of the upper wall 20 of the arch form, while end bars 23 are interposed between the opposite ends of the upper horizontal bar 22 and the outer ends of the mold sections. As shown more clearly in Figs. 6 and 8, the supporting bars 23 are cutaway at their lower ends for interlocking engagement with the outer ends of the mold clamping sections, the same having a transverse slotted opening 24 communicating with the slotted opening 25 extending at right angles thereto to form depending feet 26, 27 and 28, the foot 26 being positioned laterally of the end extension 6 of the mold section with the outer edge thereof engaging the inner face of the arm 10, the foot 28 being positioned between the shoulder 11 and arm 9, while the foot 27 is positioned outwardly of the arm 9 and adjacent the cutaway portion 8. Clamping screws 29 threaded through the openings 13 in the mold clamping sections freely pass through openings 14^a in the board 14 for reception in the threaded openings 30 in the base flanges 16 of the clamping blocks 15, the screws 29 anchoring the mold clamping sections in position together with the board 14 and clamping blocks 15. Concrete 31 or similar material is filled in the mold as shown in Figs. 1 and 4, and as illustrated in the former figure, completely embeds the I-beam 19 with the clamping blocks 15 associated therewith. After the concrete has become set, the clamping screws 29 are removed and the clamping blocks 15 remain united with the concrete and reinforcing I-beam 19 that is completely embedded in the concrete and the mold sections and arch forms with their supporting bars are removed from the molded concrete.

When it is desired to embed the I-beam in the concrete with the lower face of the base flange thereof exposed, the cooperating

mold sections are inverted as shown in Fig. 4 with the clamping lugs 12 thereof positioned for engagement with opposite side edges of the base flange of the I-beam, the side portions 21^a of the arch forms 20 being cut-away at their lower ends as at 21^b to straddle the clamping lugs 12 for support directly upon the mold sections. It is also intended to construct the mold sections as illustrated in Fig. 5 for use in supporting relatively larger I-beams, the body portions of the clamping sections being provided with longer slotted openings 4^a in which a pair of clamping bolts 5^a are mounted while the upwardly directed shoulders 3^a are of greater length to provide an extended support for the base flange of an I-beam.

From the above detail description of the invention, it is believed that the construction and operation thereof will at once be apparent, and while there are herein shown and described the preferred embodiments of the present invention, it is nevertheless to be understood that minor changes may be made therein without departing from the spirit and scope of the invention as claimed.

What is claimed as new is:—

1. In a concrete mold, a plurality of clamping members arranged in spaced relation and in spaced rows, each clamping member including separable sections, means cooperating with corresponding sides of the sections adapted for engaging opposite side edges of the flanges of reinforcing I-beams, a board adapted to be supported on the opposite corresponding sides of the mold sections, and clamping screws threaded through the mold sections, freely passing through the board and threaded into the clamping blocks.

2. In a concrete mold, a plurality of clamping members arranged in spaced relation and in spaced rows, each clamping member including separable sections, means cooperating with corresponding sides of the sections adapted for engaging opposite side edges of the flanges of reinforcing I-beams, a board adapted to be supported on the opposite corresponding sides of the mold sections, clamping screws threaded through the mold sections, freely passing through the board and threaded into the clamping blocks, and arch forms supported at their edges on the board.

3. In a concrete mold, a plurality of clamping members arranged in spaced relation and in spaced rows, each clamping member including separable sections, means cooperating with corresponding sides of the sections adapted for engaging opposite side edges of the flanges of reinforcing I-beams, a board adapted to be supported on the opposite corresponding sides of the mold sections, clamping screws threaded through the mold sections, freely passing through the

board and threaded into the clamping blocks, arch forms supported at their edges on the board, and supporting bars for the arch forms having interlocking connections 5 at their lower ends with the outer ends of the mold sections.

4. In a concrete mold, a plurality of clamping members arranged in spaced relation and in spaced rows, each clamping 10 member including separable sections, means cooperating with corresponding sides of the sections adapted for engaging opposite side edges of the flanges of reinforcing I-beams, a board adapted to be supported on the opposite corresponding sides of the mold sections, clamping screws threaded through the mold sections, freely passing through the board and threaded into the clamping blocks, and shoulders and ribs projecting 15 from one side of the mold sections to hold the board in spaced relation thereto.

5. In a concrete mold, a plurality of clamping members arranged in spaced relation and in spaced rows, each clamping 20 member including separable sections, means cooperating with corresponding sides of the sections adapted for engaging opposite side edges of the flanges of reinforcing I-beams, a board adapted to be supported on the opposite corresponding sides of the mold sections, clamping screws threaded through the mold sections, freely passing through the board and threaded into the clamping 25 blocks, arch forms supported at their edges on the board, supporting bars for the arch forms having interlocking connections at their lower ends with the outer ends of the mold sections, and shoulders and ribs projecting from one side of the mold sections 30 to hold the board in spaced relation thereto.

tions, clamping screws threaded through the mold sections, freely passing through the board and threaded into the clamping blocks, arch forms supported at their edges on the board, and shoulders and ribs projecting from one side of the mold sections 35 to hold the board in spaced relation thereto.

6. In a concrete mold, a plurality of clamping members arranged in spaced relation and in spaced rows, each clamping 40 member including separable sections, means cooperating with corresponding sides of the sections adapted for engaging opposite side edges of the flanges of reinforcing I-beams, a board adapted to be supported on the opposite corresponding sides of the mold sections, clamping screws threaded through the mold sections, freely passing through the board and threaded into the clamping 45 blocks, arch forms supported at their edges on the board, supporting bars for the arch forms having interlocking connections at their lower ends with the outer ends of the mold sections, and shoulders and ribs projecting from one side of the mold sections 50 to hold the board in spaced relation thereto.

In testimony whereof I affix my signature.

ADAM TYSKIEWICZ.
